DESIGN FOR A TEXTILE FABRIC

Jack Antkies, New York, N. Y.

Application June 16, 1938, Serial No. 77,879

Term of patent 3½ years

To all whom it may concern:

Be it known that I, Jack Antkies, a citizen of the United States of America, residing in city of New York, county of New York, and State of New York, have invented a new, original, and ornamental Design for a Textile Fabric, of which the following is a specification, reference being had to the accompanying drawing, forming part thereof.

The figure on the drawing is a plan view of a textile fabric showing my new design.

The dot and dash lines on the drawing show the design unit which unit is repeated in staggered relation, as indicated by the angles A and A'.

I claim:

The ornamental design for a textile fabric substantially as shown and described.

JACK ANTKIES.
